ELECTROMECHANICAL DEVICE

Alan Dower Blumlein and Herbert Edward Holman, London, England, assignors to Columbia Graphophone Company, Limited, London, England

Original application February 26, 1931, Serial No. 518,524. Divided and this application September 8, 1931, Serial No. 516,756. In Great Britain May 7, 1930

16 Claims. (Cl. 179—115.5)

This invention relates to electro-acoustic devices employed for the interconversion of acoustic and electrical vibrations, such as microphones, loud-speakers and the like, and is especially directed to microphonic apparatus of this type intended for use with the sound recording apparatus described in our British Patent applications Nos. 7809/30 and 14042/30.

The invention consists in an electro-acoustic device having a vibrating system consisting of a substantially rigid piston-like diaphragm connected at its outer edge to a flexible air sealing surround wherein means are provided for suppressing or controlling subsidiary resonances of the system which means do not contribute the bulk of the damping of the main resonance.

The invention also consists in an electro-acoustic device having a vibrating system consisting of a substantially rigid piston-like diaphragm connected at its outer edge to a flexible air sealing surround wherein means are provided for applying shielding and/or damping to the surround only.

The invention further consists in an electro-acoustic device as set forth above wherein the piston-like portion of the diaphragm is composed of light wood, such as balsa wood, covered on either side or on both sides by a thin plate of aluminium or other light metal or alloy.

The invention also consists in an electro-acoustic device as set forth above wherein the main resonance of the device is controlled by electromagnetic damping.

The invention also consists in an electro-acoustic device as set forth above wherein a coil is adapted to move in a magnetic field.

Further features of the invention will appear from the following description of a modification thereof which will be more readily understood by reference to the accompanying drawing representing a longitudinal section through the axis of a microphone constructed in accordance with the invention.

The principles upon which the invention is based will be set forth by consideration of a microphone consisting of a piston-like diaphragm caused to move by sound waves impinging thereupon. In order that this diaphragm shall be free from resonances due to its own flexure it is desirable to make it rigid. Also it is desirable that the mass of the diaphragm be as low as possible in order that it shall respond amply to the high frequency sound waves incident on it. One object of the present invention is to make a diaphragm which will meet the conflicting re-

quirements of great rigidity and low mass, and this object is met if the diaphragm is made of a three-ply construction, consisting of two thin layers of a light metal such as aluminium enclosing a centre of light wood such as balsa wood. 60

If air is permitted to pass freely from the front to the back of such a diaphragm, the response of the device at all low frequencies will be impaired due to the diaphragm receiving almost equal variations of sound pressure on both its front and back faces. Therefore it is necessary to provide a closed cavity (or baffle) containing (or shielding) the air behind the diaphragm and to supply an air seal between the sides of the diaphragm and the sides of the air cavity. Such a seal for a microphone cannot in practice take the form of a frictional packing on account of the delicate nature of the movements of the diaphragm; and therefore in accordance with the invention a thin elastic surround is provided between the diaphragm and the sides of the cavity. The diaphragm then forms a rigid piston closing the mouth of a closed cavity, the edge of the diaphragm being sealed by a thin surround which stops the direct access of air to the cavity, but nevertheless permits the diaphragm to move. The surround which forms the air seal may conveniently support the diaphragm. 75

According to one embodiment of the invention the diaphragm has attached to its rear surface (i. e. the surface within the cavity and not exposed directly to incident sound waves) a coil which can move freely in a magnetic field provided by an electromagnet, or permanent magnet provided. This coil serves to convert the mechanical movement of the diaphragm into electric impulses and may also be utilized to provide damping for the resonance of the mass of the diaphragm and its elastic constraints. Such damping may be provided by closing the moving coil with a circuit having a low impedance at frequencies close to the resonance of the oscillating mechanical system by which means an E. M. F. generated by the moving coil will cause damping currents to flow through the moving coil. It is thus possible to control the main resonance of the microphone and make the response such that it may be easily equalized by suitable electrical circuits. In order that this resonance may be well controlled, it is convenient to make the main resonant frequency as low as possible, and in order to do this it is necessary to make the surround thin and flexible. Such a thin flexible surround is liable itself to resonate due to high frequency sound waves impinging on it; 110

the resonance being due to the mass of the surround (and coupled air mass) resonating with the stiffness of the surround (and coupled air stiffness). At the frequency of this resonance the mass reactance of the piston diaphragm is so high that it acts almost as a rigid support to the inner edge of the surround; but nevertheless a violent resonance of the surround is sufficient to modify the movement of the piston diaphragm and so modify the response of the microphone.

A further object of the invention is to reduce or prevent the resonance of the surround so that the response of the microphone is controlled and regular at high frequencies, and in order to do this the surround may be shielded from direct access of high frequency waves by means of a shield positioned close to the surround in front of it. Further the surround may be provided with damping in order to damp its resonance, since if its resonance is well damped it will be unable to affect appreciably the movement of the comparatively heavy piston diaphragm. Such damping may take the form of a rigid member fixed to the body of the microphone and extending over the surface of the surround, and very close to it, thus providing viscosity damping due to the thin film of air trapped between the surround and the fixed member. Such damping must not be confused with damping applied to control the main resonance of the microphone. The degree of damping necessary to control the resonance of the thin light surround is much smaller than that necessary to control the main resonance of the microphone. Further, the value for the damping applied to the surround has no very critical effect upon the response of the microphone, provided that this damping is sufficient to reduce materially the effects of the surround resonance on the movement of the piston diaphragm. Were an attempt made to control the main resonance by means of this damping, the response of the microphone at its main resonance would depend entirely on the damping provided; and also, with the degree of viscosity damping easily obtainable, the resonance peak would be very sharp and difficult to equalize.

Hence according to the invention a piston-like diaphragm is used, sealed in the mouth of a cavity by a thin flexible surround, which surround may also serve to support the diaphragm. The main resonance of the mass of the piston diaphragm (and anything attached to it such as a moving coil) with its elastic constraint is controlled by special damping such as electromagnetic damping. The resonance or resonances of the thin surround are prevented and/or controlled by special shields interposed to prevent the incidence of direct H. F. waves on the surround and by special damping applied specifically to the surround. Such shielding may take the form of a member extending over the front of the surround and close to it. The damping for the surround may take the form of a member lying very close to either the front or back of the surround and thus damping it due to the viscosity of the trapped air. Alternatively members may be placed both in front of and behind it so as to damp it more effectively or a packing of cotton wool or other damping material may rest lightly against the surround. In order that the thin surround may be flat it is desirable to arrange that it is suitably stretched when in position. By varying the amount of stretch a

useful control of the main resonant frequency may be obtained.

Fig. 1 attached shows a section through the axis of a microphone according to this invention constructed in accordance with the above principles. Figure 2 represents in simple form a part of the circuit connected to the microphone wherein the elements are arranged to provide electromagnetic damping for the diaphragm.

The diaphragm comprises a layer of balsa wood *a'* covered on each side by a thin sheet of aluminium, *b'*, pressed and waxed together to form a rigid structure. Alternatively the diaphragm may be formed only of balsa wood or other wood, allowing a highly rigid light diaphragm to be constructed; or it may be built up from a flat diaphragm of aluminium or other light alloy with cones of similar material attached to the back in order to brace the diaphragm to rigidity. The support may consist of a light elastic connection at the edges of the diaphragm and in the form shown consists of an extended annulus *c'* of the back aluminium covering sheet. This sheet is pressed into the dish-shaped form shown in order that the plane of support by the annulus *c'* may pass through the centre of gravity of the system supported. For increased flexibility the annulus *c'* may be much thinner than the plate proper, this thinning being accomplished, for example, after the plates are fixed to the wood, by dissolving off some of the metal with caustic soda.

To the back of the diaphragm may be attached a coil *d'* formed of thin enamelled aluminium wire wound on a thin aluminium former *e'* which may be fixed to the diaphragm by rivets *f'*. In order to avoid short circuiting turns the coil former may have in it a longitudinal saw cut extending almost to the diaphragm and may, before use, be insulated by a coating of aluminium hydroxide.

Conveniently the microphone may be more or less bottle-shaped (as shown) with a maximum diameter of, say, 3 inches, the body and neck of the bottle forming the magnetic system, while an attached holder, *g'*, for the diaphragm and moving coil, forms the bottom of the bottle. This holder *g'* may be fitted to the outer pole piece *h'* of a small pot magnet by three, or more, centering screws *i*; and the diaphragm and moving coil secured against a step *j'* of the holder, 125 between washers *k'*, by means of a screw threaded clamping ring *l'*. Held by screw threads tapped within the clamping ring *l'* is a diaphragm stretching ring *m'* which, on being screwed inwards, brings a small rounded ridge 130 *n'* to bear against the annulus *c'* (which on account of its frailty and flabbiness tends to become wrinkled and distorted) thereby stretching it smooth and taut. As a matter of little importance it is to be noted that by means of this stretching ring a degree of control on the natural frequency of the diaphragm is also available. As well as carrying the rounded ridge *n'*, the stretching member forms a shield over the thin surround, and to some extent serves to damp resonances in the surround. It will be seen from the drawing that the stretching ring has a portion which passes very close to the surround and lies close to the sloping sides of the piston portion. This shield serves, as explained, to reduce 145 or prevent resonances in the surround. Increased damping on the surround can be obtained by making a small cavity between the stretching ridge *n'* and the smooth portion of the shielding and damping surface; such a cavity may consist 150

of a groove in the stretching ring immediately inside the stretching ridge n' and such a groove may be say 1 mm. deep and 1 mm. broad. By making the damping surface lie very close indeed to the surround, at a point just adjacent to this groove, it can be arranged that the damping is increased due to small movements of the surround forcing air into the groove through this narrow neck between the damping surface and the surround. These effects may be enhanced by fitting another damping surface close to the surround at the back of the diaphragm.

To protect the diaphragm from accidental damage the aperture in the ring m' through which the sound waves proceed may be formed only of a number of small holes o' drilled through the plate thus forming a grille which seems not to affect the acoustic properties of the device although serving admirably for protection.

The magnetic circuit as previously mentioned comprises a small pot magnet, and is formed of an outer pole piece h' , the case of the microphone p' , a rear plate, q' , and a centre pole piece r' , on which are mounted the windings s' . Between the inner and outer poles is a gap (which is shown excessively large in the drawing for convenience of illustration) in which the moving coil is positioned, and in order that the dimensions of this gap shall be correct a spacing ring t' of brass or, preferably, cadmium bronze, may be provided. This may be a force fit on the inner pole piece and a good fit in a groove in the outer pole piece and serves not only to space the poles correctly but also to reduce the inductance of the moving coil, being magnetically coupled with it and having a low resistance.

The inner pole piece is preferably made of cobalt iron or other material having a high saturation density; but the flux density in the other portions of the circuit may be kept quite low, and good magnetic iron of thickness sufficient for the strength required may conveniently be used. The windings s' fill the body of the microphone between the pole pieces, and are preferably formed of two different gauges of wire, the inner turns being of thinner gauge than the outer.

In order to avoid undue elastic restraint on the diaphragm by the air between it and the poles of the magnet it is desirable that a reasonably large volume be enclosed. To this end a cavity u' is provided between the holder g' and the outer pole piece h' ; and communicating with the rear of the diaphragm by an annular passage v' , in which may be inserted a ring of loose cotton wool w' to damp resonance between the mass of air in the passage and the stiffness of the air in the main cavity. To avoid restraint due to air trapped within the moving coil former between the diaphragm and the inner pole piece holes may be drilled in the former as shown. To prevent short circuited turns in the magnetic field the coil former may have a saw-cut x' extending longitudinally over substantially its whole length. The leads from the moving coil as shown pass through the annular passage and cavity to terminals on the holder g' but if desired the terminals may be located at any other suitable position such for example as at the rear end of the microphone.

The moving coil may be shunted by a circuit which in its simplest form consists of an inductance resistance and condenser in series, which circuit is designed to have a low impedance at frequencies close to resonance but a high impedance at frequencies remote from resonance, so that damping is provided electromagnetically but

the efficiency of the device is not impaired at those frequencies where it is least efficient. Similarly other circuits may be used for this purpose as shown in Fig. 2 or as described in U. S. A. patent application No. 518,524, filed Feb. 26, 1931.

In Figure 2 of the accompanying drawing the damping circuit shown is connected in parallel with the microphone which is indicated by a symbolic representation of a coil d' corresponding to the speech coil identified by the same reference letter in Figure 1.

Should it be desired to form a loud-speaker in accordance with this invention, this may be done with a construction very similar to that shown for the microphone, except that a horn or baffle may be fitted at the mouth in front of the diaphragm. The shield on the surround then prevents the surround generating an excess of high frequency waves when it resonates.

Having now described our invention, what we claim as new and desire to secure by Letters Patent is:—

1. An electro-acoustic device having a vibratory system comprising a substantially rigid piston-like diaphragm connected at its outer edge to a flexible air-sealing surround, electromagnetic damping means acting directly on the diaphragm to damp resonant vibrations thereof, and viscous means arranged to damp vibrations of the surround.

2. An electro-acoustic device having a vibratory system comprising a substantially rigid piston-like diaphragm supported solely by a flexible air-sealing surround connected to the outer edge of said diaphragm, electromagnetic damping means acting directly on the diaphragm to damp resonant vibrations thereof, and viscous means arranged to damp vibrations of the surround.

3. An electro-acoustic device having a vibratory system comprising a substantially rigid piston-like diaphragm connected at its outer edge to a flexible air-sealing surround, electromagnetic damping means acting directly on said diaphragm to damp resonant vibrations thereof, and a member positioned very near to said surround to trap a thin film of air between itself and the surround, said air film providing viscous damping on resonant vibrations of said surround.

4. An electro-acoustic device having a vibratory system comprising a diaphragm formed of light wood having a thin metal facing on each side, a flexible air-sealing surround extending from the outer edge of said diaphragm, electromagnetic damping means acting directly on the diaphragm to damp resonant vibrations thereof, and viscous means arranged to damp vibrations of the surround.

5. An electro-acoustic device having a vibratory system comprising a diaphragm formed of balsa wood having a thin metal facing on each side, said metal being extended beyond the wooden base to form a flexible air-sealing surround for the diaphragm, electromagnetic damping means acting directly on the diaphragm to damp resonant vibrations thereof, and viscous means arranged to damp vibrations of the surround.

6. An electro-acoustic device having a vibratory system comprising a substantially rigid piston-like diaphragm connected at its outer edge to a flexible air-sealing surround clamped at its perimeter to a rigid holder so that the diaphragm and surround cover the mouth of a closed cavity of large size, electromagnetic damping

means acting directly on the diaphragm to damp resonant vibrations thereof, and viscous means arranged to damp vibrations of the surround.

7. An electro-acoustic device having a vibratory system comprising a substantially rigid piston-like diaphragm connected at its outer edge to a flexible air-sealing surround clamped at its perimeter to a rigid holder so that the diaphragm and surround cover the mouth of a closed cavity of large size, electro-magnetic damping means acting directly on the diaphragm to damp resonant vibrations thereof, viscous means arranged to damp vibrations of the surround, said closed cavity comprising a portion immediately behind the diaphragm from which a narrow annular passage communicates with another portion more remotely disposed from the diaphragm which forms the main expansion chamber for the enclosed air.
- 20 8. An electro-acoustic device as claimed in claim 7 wherein a packing of loose cotton wool is inserted in said narrow annular passage to damp resonant oscillatory movements of air between the said two portions of the enclosed 25 space.
9. An electro-acoustic device according to claim 1 comprising means for adjusting the tension of said surround.
10. An electro-acoustic device according to claim 1 comprising an adjustable stretching ring having a smooth ridge extending round said diaphragm adapted to press against said surround for adjusting the tension thereof.
- 30 11. An electro-acoustic device according to claim 3 wherein said member adapted to damp said surround comprises an annular ring separated from the surround over at least one third of its area by a distance not greater than one tenth of a millimeter.
- 40 12. An electro-acoustic device according to claim 3 wherein said member adapted to damp said surround comprises an annular ring separated from the surround over at least one third of its area by a distance not greater than one

tenth of a millimeter, said annular ring having a groove cut in its surface adjacent to the outer edge of said surround.

13. An electro-acoustic device comprising a substantially rigid piston-like diaphragm, a former attached to said diaphragm, an electric coil wound on said former, means for providing a steady magnetic field in which said coil is immersed, a flexible air-sealing surround extending from the edge of said diaphragm and forming the sole means of support for said diaphragm assembly, electromagnetic means acting through the medium of said coil directly upon said diaphragm to damp resonant vibrations thereof, and viscous means to damp vibrations of said surround.

14. An electro-acoustic device according to claim 13 wherein the centre of gravity of the whole vibratory system comprising said diaphragm, former and coil lies in the plane of support of said surround.

15. An electro-acoustic device according to claim 13 wherein said means for providing a steady magnetic field comprise a central inner magnetic pole piece projecting into said former, and an outer encircling magnetic pole piece surrounding said former, thus providing a field radially perpendicular to said former.

16. An electro-acoustic device having a vibratory system comprising a substantially rigid piston-like diaphragm connected at its outer edge to a flexible air-sealing surround and an electric coil attached to said diaphragm, electromagnetic damping means acting directly upon said diaphragm and comprising a shunt circuit connected across said coil having an impedance which is low at frequencies in the neighbourhood of mechanical resonance of said vibratory system but high at frequencies removed therefrom, and viscous means arranged to damp vibrations of said surround.
